COMBINED TRAY AND COVER FOR A FISH AQUARIUM

Marcel M. Arnould, East Orange, N.J.

Application February 12, 1959, Serial No. 54,579

Term of patent 14 years

(Cl. D91—2)

FIG.1.

FIG.2.

Fig. 1 is a top perspective view of the combined tray and cover for a fish aquarium embodying my new design, and

Fig. 2 is a bottom perspective view.

I claim:

The ornamental design for a combined tray and cover for a fish aquarium, substantially as shown.
